UNITED STATES PATENT OFFICE.

CLARENCE A. YATES, OF LOS ANGELES, CALIFORNIA, ASSIGNOR OF ONE-HALF TO
FRANK E. COTTER, OF LOS ANGELES, CALIFORNIA.

TONE ARM AND YOKE FOR PHONOGRAHS.

Application filed May 7, 1923. Serial No. 637,057.

My invention relates to sound reproducing apparatus of that type embodied in my co-pending application filed October 1, 1921, serially numbered 504,683, in which sound waves are regenerated by a conical shaped fibrous tympanum without the employment of an amplification device.

It is a purpose of my present invention to provide a sound reproducing apparatus of the above described character having a vibration conducting mechanism including a tubular member provided with a reed-like extremity which is associated with a rigidly sustained stylus holder in such manner that the vibrations set up by the stylus traversing a sound record effect molecular vibrations of the tubular member which, although being of increased intensity, are transmitted to the tympanum without distortion so as to produce sound waves of unusually large volume and great carrying power.

It is also a purpose of my invention to provide a sound reproducing apparatus in which the sound wave conducting mechanism embodies a bridge-like member rigidly mounted for molecular vibration, with the reed-like extremity of the tubular member associated therewith so as to freely respond to the molecular vibrations thereof whereby, the sound producing undulations of a record are caused to be converted into molecular vibrations and accurately transmitted to the tympanum.

A further purpose of my invention is a provision of a mounting for the tympanum and vibration conducting mechanism which not only allows of the necessary universal adjustment of these elements in permitting the stylus to accurately follow the sound groove of a record, but utilizes the weight of the tympanum and conducting mechanism to counterbalance each other so that the pressure imparted to the stylus will be so slight as to prevent wear of the vibration producing undulations of a record, but sufficient to cause the accurate reproduction of the vibrations by the stylus.

Another purpose of my invention is a provision of a stylus holder which sustains the stylus at such an angle with respect to the plane of a disc record as to prevent the point of the stylus from engaging the bottom of the sound groove thereby eliminating the noises generated incident to the contact of the stylus point with the bottom of the sound

groove. Further, the stylus holder allows of the projection of the stylus from the holder various distances whereby the intensity or volume of the sound waves reproduced can be regulated at will.

60

Although I have shown and will describe only one form of sound reproducing apparatus embodying my invention, it is to be understood that various changes and modifications may be made herein without departing from the spirit of the invention and the spirit and scope of the appended claims.

65

In the accompanying drawings:—

Figure 1 is a view showing in side elevation one form of sound reproducing apparatus embodying my invention in applied position within a cabinet.

Fig. 8 is a fragmentary view showing in side elevation that portion of the mechanism shown in Fig. 7.

Fig. 9 is a transverse sectional view taken on the line 9—9 of Fig. 7.

95

Fig. 10 is a transverse sectional view of a sound groove of the record shown in Fig. 1 with the stylus in applied position.

Similar reference characters refer to similar parts in each of the several views.

100

Referring specifically to the drawings and particularly to Fig. 1, my invention in its present embodiment is shown as housed in a cabinet K having a filigreed front side 15, and a rear side provided with an opening 105 controlled by a door 16. Through this opening access is had to the interior of the cabinet for manipulating the apparatus and applying and removing sound records to and from the turntable. Within the cabinet K is 110

- located a housing 17 which contains the mechanism for driving a turntable 18 upon which a disc record 19 is adapted to be supported.
- The sound reproducing apparatus embodying my invention comprises, in the present instance, a standard 20 arranged in front of the housing 17 and rigidly braced by an arm 21. Upon the upper end of the standard 20 is secured, as clearly shown in Fig. 3, a mounting including a base 22 provided centrally thereof with a bearing collar 23, and extending upwardly from the collar is a substantially L-shaped arm 24 provided at its horizontal portion with an adjustable bearing element 25. A yoke 26 of rectangular outline is provided with a depending extension 27 which is journaled in the collar 23. The upper portion of the yoke 26 is recessed as indicated at 28 to provide a bearing for the member 25. Thus the members 25 and 27 cooperate to allow limited rotational movement of the yoke about a vertical axis. The yoke 26 carries in its vertical portions a pair of screws 29 having conical bearings formed on their inner ends for engagement with two recesses provided in a supporting arm 31. The arm 31 is of tubular form, as clearly shown in Figs. 2 and 3, and is provided with cutaway portions 32 to accommodate the yoke 26 and thus provide for the necessary movement of the arm upon the yoke in applying the sound reproducing apparatus to or removing the same from the sound record. Through the medium of the screws 29, the arm 31 is capable of swinging movement about a horizontal axis, and by virtue of the mounting of the yoke 26, it will be clear that the arm 31 is also capable of being swung about a vertical axis.
- The various elements forming the universal joint shown in Fig. 3 form what is technically known as a gimbal joint.
- As shown in Figs. 2 and 3 the arm 31 is formed of relatively hard steel or other suitable metal and of such ponderous proportions and weight that they will be unresponsive to the rigid mechanical vibrations of the stylus. As shown, the arm 31 is connected to one end of the casing 33 and disposed at an angle with respect to the casing so that when the apparatus is in active position it will occupy a position inclined with respect to the perpendicular, while the casing 33 will assume a position substantially parallel to the turntable 18.
- As shown in Fig. 3, the casing 33 contains a vibration transmitting member 34 which is of tubular form and provided with relatively thick walls so that it will not respond to the mechanical vibrations. This transmitting member, as clearly shown in Figs. 6 and 7, is provided at one end with a reed-like extension 35, while adjacent such extension the tube is beveled as indicated at 36 so that the tube is tapered in the direction of the extension 35 for a purpose which is hereinafter described. The opposite end of the member 34 is supported concentrically within the casing by means of a felt plug 37 bored to receive the tube 34 and of a diameter to snugly fit within the end of the casing 33. The adjacent end of the tube 34 is threaded interiorly as indicated at 38 in Fig. 6, to receive a screw 39. This screw 39 supports a pair of conical shaped clamping plates 40 which embrace the apex of a conical shaped tympanum 41 formed of fibrous material such as paper, cardboard, or the like. The adjacent end of the tube 34 is provided with beveled edge 42 so as to conform to the contour of the inner plate 40 and thus provide a snug fit between the two. The screw 39 carries a pair of nuts 43 the inner one of which engages a washer 44 having a beveled edge to snugly fit the outer clamping plate 40. The outer nut serves as a lock nut for securing the inner nut against rotation.
- As shown in Fig. 7, the reed-like extension 35 is connected to the bridge portion 45 of a stylus holder through the medium of an extension 46 rigidly secured to the portion 45 and having a threaded projection 47 to receive a nut 48 for securing the extension 35 to the extension 46. The bridge portion 45 is rigidly secured to a supporting bar 49 through the medium of screws 50 which extend loosely through suitable openings in the bar 49 and which threadedly engage the bridge portion 45 adjacent the ends thereof, as clearly shown in Fig. 6. The bar 49 is provided with terminal projections 51 which receive screws 52 for rigidly securing the bar within the casing 33, as clearly shown in Fig. 3. The screws 50 serve to hold the bridge portion 45 in engagement with bearing pins 53 seated within the bar 49, as shown in Fig. 6, which are arranged to engage the bridge portion at the opposite ends thereof.
- Extending medially from the bridge portion 45 is a stylus supporting arm 54 having a depending extension 55 formed with a duct 56 which is co-extensive in length with the extension so as to accommodate styli of different lengths or to allow the longitudinal adjustment of a stylus so that it can be made to project various distances from the extension. The stylus designated at 57 is retained in any adjusted position within the extension by means of a set screw 58.
- In the operation of my invention the casing 33 serves as a handle to move the sound conducting mechanism and the tympanum upon the mounting so that one can apply the stylus to the record 19 or move the same to inactive position at one side of the turntable. It will be understood that the mounting for

the arm 31 and the yoke 26 allows the stylus to follow the sound groove of the record 19. With the stylus in applied position upon the record to engage the record's undulations, the stylus holder is subjected to molecular vibrations by virtue of the fact that the bridge member 45 is rigidly secured to the bar 49. This molecular vibratory movement of the bridge member 45 is transmitted to the 10 reed-like extension 35 through the extension 46 thereby setting up in the conducting member 34 molecular vibrations of greatly increased intensity as compared to the vibrations occurring in the stylus holder. It will 15 be understood that the reed-like member 35 is extremely sensitive to vibrations because of its attenuated form, and that as a consequence the molecular vibrations of the stylus holder are intensified during transmission from the holder to the member 34. With the member 34 subjected to intensified molecular vibrations, such vibrations are directly transmitted to the tympanum as the latter is solely substantiated upon the member, and by virtue of the conical formation of the tympanum these vibrations serve to bodily move the same thus converting the vibrations into sound waves. I have found by experiment that the sound waves produced by the tympanum through the sound conducting mechanism embodying my invention are not only of large volume and great carrying power, but of unusual clarity and resonance both as to the tones of high 35 and low pitch as well as the tones of medium pitch, and in fact I obtain a reproduction of tones ordinarily lost in the graphophones heretofore produced.

In order to secure this superior tone reproduction, it is necessary that the stylus holder be formed of case hardened metal such as steel, tungsten, or the like in order that there may be no excessive molecular vibrations therein when the stylus is excessively vibrated. To carry out this idea the member 34 is made of relatively hard metal, which may or may not be of the same degree of hardness as the member 34. Both the casing 33 and the arm 31 are preferably 50 formed of metal but as these elements are not subjected to molecular vibrations, the degree of hardness of the metal of which they are formed is immaterial.

As previously mentioned, the stylus is supported through the medium of the stylus holder so as to occupy an inclined position with relation to the record to prevent its point from actually contacting with the bottom of the sound groove of the record. 60 As illustrated in Fig. 10, the point of the stylus is elevated from the bottom of the sound groove indicated at 60, while the sides of the stylus point bear upon the undulations designated at 61 of the sound groove. 65 It will thus be seen that the stylus is free to

respond to the undulations of the record while it is at the same time held out of engagement with the bottom of the sound groove thereby eliminating the noise incident to such engagement.

The stylus 57 is of a type having a blunt point forming a close fit between the opposite sides of the groove and thereby supporting the stylus so that its point does not engage the bottom face of the groove.

From a consideration of Fig. 2, it will be seen that the fulcrum point 29 for the arm 31 is disposed at one side of the connection between the casing 33 and the tympanum 41 thus causing the weight of the tympanum to partly counterbalance the weight of the casing and arm so as to render the pressure exerted by the casing and arm upon the stylus 57 relatively slight. As a consequence, the pressure exerted by the stylus upon the record is correspondingly slight so that the undulations of the record are not subjected to any undue wear. I consider this counterbalancing feature of the weights of the casing and tympanum a very important part of my invention because I have found in practice that after repeated use of a single record no appreciable wear of the record is apparent, and as a matter of fact, the quality of the sound reproduction appears to improve with use.

What I claim is:—

1. A sound reproducing apparatus comprising in combination a gimbal joint, an arm connected thereto, a tubular casing secured to the arm near one end of the casing, a bridge secured to the opposite end of the casing, a stylus holder spaced from but connected to the bridge, a vibration absorbing plug at the opposite end of the casing from the bridge, a vibration transmitting hollow bar secured to the stylus holder, and a tympanum mounted on the opposite end of the bar.

2. A sound reproducing apparatus comprising a casing, a stylus holder including a bridge portion sustained within the casing, a lateral extension on the bridge portion, a tube sustained concentrically within the casing, a reed-like extension formed in one end of the tube and connected to said lateral extension, and a tympanum of conical form supported at its apex upon the other end of said tube.

3. In a sound reproducing apparatus, a tubular supporting casing, a bar secured at one end of the casing, a stylus holder including a bridge, relatively sharp bearing members interposed between the bridge and the bar, fastening members engaging the bar and bridge for holding the bridge in contact with the said bearing members, a stylus secured to the holder, and a sound transmitting rod also secured to the holder and passing through the casing.

4. In a sound reproducing apparatus, a stylus holder, means for supporting the stylus holder, a sound transmitting rod having a central bore therethrough and cut away at one end completely across the bore and leaving a thin reed-like portion, means for connecting the reed portion to the stylus holder, and a tympanum supported by the other end of the rod.
- 10 5. A sound reproducing apparatus comprising in combination a tubular casing, a gimbal joint, a support therefor connected to said gimbal joint, a bar having terminal projections with screws securing the projections rigidly to one end of the casing, a stylus holder having a bridge, sharp bearing

members spacing the bar and bridge, screw threaded members holding the bar and bridge pressed toward each other, a stylus connected to the bridge, a rod having a central bore therethrough and cut away at one end completely across the bore leaving a reed-like portion at one end, a pin securing the reed-like portion to the stylus holder, said rod extending through the casing and supported at the opposite end from the stylus holder, and a tympanum secured to the end of the rod by a screw threaded into the bore of the rod.

In testimony whereof I have signed my name to this specification.

CLARENCE A. YATES.
